UNITED STATES PATENT OFFICE.

THEODORE AHLBORN, OF CHICAGO, ILLINOIS, ASSIGNOR TO WATERLOO CEMENT MACHINERY CORPORATION, OF WATERLOO, OHIO, A CORPORATION OF OHIO.

CONCRETE-MIXER OR THE LIKE.

1,284,959.

Specification of Letters Patent. Patented Nov. 19, 1918.

Application filed March 8, 1913. Serial No. 752,835.

To all whom it may concern:

Be it known that I, THEODORE AHLBORN, a citizen of the United States, residing at Chicago, in the county of Cook and State 5 of Illinois, have invented certain new and useful Improvements in Concrete-Mixers or the like, of which the following is a description.

My invention belongs to that general class 10 of devices known as mixers, and relates particularly to a convenient, portable concrete mixer of the type known as a single-batch mixer. The invention has among its objects the production of a device of the kind 15 described that is extremely simple, convenient, efficient and satisfactory, that may be manufactured and sold at comparatively low cost and used wherever found applicable. It is particularly suitable for small 20 jobs, as it may be very conveniently transported from place to place, and may be satisfactorily manually operated, if desired.

To this end my invention consists in the 25 novel construction, arrangement, and combination of parts herein shown and described, and more particularly pointed out in the claim.

In the drawings, wherein like reference 30 characters indicate like or corresponding parts:—

Figure 1 is a side elevation of my improved mixer.

Fig. 2 is a top elevation of the same.

Fig. 3 is a central vertical sectional view 35 taken substantially on line 3, 3 of Fig. 1, the mixing drum turned to its vertical position, and

Fig. 4 is a side elevation of the tilting handles.

Referring to the drawings, 1 is a suitable frame bar having the ends bent up to form substantially a U, and thence extended as at 2 to form axles for the wheels 3, which support the frame. Mounted on the axle 45 part at each side is a plate 4, or its equivalent, to which is secured a frame consisting of the side bars 5 and an end bar 6. The frame may be made of any suitable material; as shown, it is made of pipe, giving 50 a very substantial, as well as a simple and economical construction. Arranged at the center of the frame bar 1, and pivotally supported thereon, is a shell or receptacle 8, which is preferably formed as at 10 at the center, so as to substantially form a cone.

The receptacle may be pivotally secured to the frame in any desired manner. As shown, it is provided with a pin 7 secured thereto, which extends through an extension 11, and is secured in position by a nut 60 11'. If desired, a chamber 12 may be provided, in which may be packed a suitable lubricant. The pin or shaft 7 is shown secured in place by a babbitt 7', 7" being depressions in the shaft, in which the babbitt 65 may flow. The part 9 of the shell is also preferably extended as at 9', and ball bearings, or their equivalents, provided for carrying the drum. The shell 8 is provided with an extended shell part or rim 14, the 70 two parts forming the mixing drum, which is open upon one side. One or more blades 15 for mixing and breaking the material may be arranged within the drum.

Any suitable means may be provided for 75 rotating the drum, as well as tilting the same for charging or to discharge the contents. For rotating the drum, I preferably provide a flange 16, having suitable teeth for engagement with a pinion 17 secured 80 upon a shaft 18, which may be rotated in any desired manner. A very simple construction is shown in the drawings, in which a fly wheel 19, having a hub 20 is secured to the shaft 18. A bar 21 is pivotally connect- 85 ed at 22 to the fly wheel, and at 23 at the opposite end to an arm 24. The arm 24 is pivotally supported at 25 by a bracket 26, and is provided with arms 28 on each side, in which operating handles 29 may be positioned. The bracket 26 may be formed as at 27, and is secured to the side bar 5 in any suitable manner.

At the opposite side of the frame 1 is arranged a member 31, which is secured to the 95 axle 2, the member being provided with one or more arms 32. The purpose of the arms 32 is to provide a simple construction for rocking the frame 1, and thereby tilting the mixing drum, to charge the same or to discharge the contents. A bracket 33 is secured at 34 to the frame part 5 on this side of the frame 1, the same being similar to the bracket 26 upon the opposite side. Secured to the brackets 26 and 33 are brackets 35, 100 which carry a chute 36 having its discharge side or spout 37 terminating over the open end of the drum when tilted, as shown in Fig. 2, so that material discharged into the chute will enter the drum. A board or plat- 105

form 38 is also secured to the side bars 5, 5, to which is secured a runway 39, the same being preferably hinged as shown, so that it may be folded back when the device is transported to where desired.

In operation, assuming that the drum is in the position shown in Fig. 1, a wheelbarrow may be pushed upon the runway 39 up to the chute, and dumped into the chute by elevating the handles. The material is discharged into the drum. If either one or both of the handles are then operated or pumped, the same through the arm 24 and connecting bar 31, drives the shaft 18 and pinion 17, and rotates the mixing drum upon its axis. The mass or mixture within the drum is thoroughly mixed by the rotation of the drum, the same being agitated by the blades 15, which throw it upon the cone surface 10 and about the drum. After the same is sufficiently mixed, the latch 40 is then released so that the drum may be swung into the discharging position, by the handles 32, so that it may be discharged into a wheelbarrow, or other receptacle, placed to receive the contents. It will be noted that the mixer is extremely simple and portable. It is particularly adapted for small jobs or repairing work, but its use is not confined to this, for its capacity is limited only by the size of the drum, which is preferably made of a size most suitable for manual operation. Therefore, it will, of course, be understood

that while manual operating mechanism is shown, a gas engine or equivalent source of power, may be provided for rotating the drum.

Having thus described my invention, it is obvious that various immaterial modifications may be made in the same without departing from the spirit of my invention, hence I do not wish to be understood as limiting myself to the exact form, construction, arrangement, or combination of parts herein shown and described, or uses mentioned.

What I claim as new and desire to secure by Letters Patent is:—

In a mixing device, the combination of a mixer drum with a pivoted supporting part having means between its pivots for rotatably carrying said drum, a pivoted frame carried by said supporting part, means for rocking said supporting part including an arm; a bracket rigidly secured to said frame, and a pivoted gravity latch secured to said bracket and normally adapted to engage said arm and hold the same in locked position substantially as described.

In testimony whereof, I have hereunto signed my name in the presence of two subscribing witnesses.

THEODORE AHLBORN.

ROY W. HILL,
CHARLES I. COBB.

Correction in Letters Patent No. 1,284,959.

It is hereby certified that the residence and State of incorporation of the assignee in Letters Patent No. 1,284,959, granted November 19, 1918, upon the application of Theodore Ahlbom, of Chicago, Illinois, for an improvement in "Concrete-Mixers or the Like," was erroneously given as "Waterloo, Ohio, a corporation of Ohio," whereas said residence and State of incorporation should have been given as *Waterloo, Iowa, a corporation of Iowa*, as shown by the records of assignments in this office; and that the said Letters Patent should be read with this correction therein that the same may conform to the record of the case in the Patent Office.

Signed and sealed this 24th day of December, A. D., 1918.

[SEAL.]

F. W. H. CLAY,

Acting Commissioner of Patents.
